UNITED STATES PATENT OFFICE.

HERALD CATLETT AND EDWIN ROBERTSON, OF FAIRMOUNT, ILLINOIS.

FLOOD-FENCE.

SPECIFICATION forming part of Letters Patent No. 449,204, dated March 31, 1891.

Application filed October 21, 1890. Serial No. 368,872. (No model.)

To all whom it may concern:

Be it known that we, HERALD CATLETT and EDWIN ROBERTSON, citizens of the United States, residing at Fairmount, in the county 5 of Vermilion and State of Illinois, have invented certain new and useful Improvements in Flood Fences or Gates; and we do hereby declare that the following is a full, clear, and exact description of the same, reference being 10 had to the annexed drawings, making a part of this specification, and to the letters of reference marked thereon.

Figure 1 of the drawings represents a view showing our improved flood-fence in use; Fig. 15 2, a top plan view of the fence; Fig. 3, a sectional elevation on an enlarged scale, and Fig. 4 a side view thereof partly in broken section.

The present invention has relation to flood-fences which are used for closing gaps in a line of fence where it crosses streams of water; and the object thereof is to provide such a fence as will be simple in construction, effective in operation, and possess the necessary 25 strength and durability, which objects are attained by the construction substantially as shown in the drawings and hereinafter described and claimed.

In the accompanying drawings a gap in 30 which a stream of water flows is shown in Fig. 1 between the banks upon which the ordinary fence is built, in order better to illustrate the application of the invention. The base of the flood-fence consists of the two 35 clamping-plates A B, between which are held the spring-wire pickets C, and the clamping-plates are firmly held in position upon the bed of the stream by suitable metal pins or stakes a.

40 We do not wish to be confined to any special means of anchoring the fence or holding it in position on the bed of the stream, as it is evident that any well-known and desirable means may be employed without departing 45 from the principle of our invention, and therefore have shown one of many means that could be employed to attain this object, the pins or stakes being preferably bolted to the plates A B, and any number may be used, as 50 found desirable.

The clamping-plates A B have holes b at suitable distances apart, through which screw-

bolts c pass, and by means of the nuts d on the bolts the two plates may be drawn together against the lower ends of the pickets, 55 which are located between them.

The lower ends of the pickets C have coiled springs e and terminate at their lower extremity in eyes f, through which the bolts pass. If desired, washers may be interposed between 60 the eyes of the pickets and the plates, and also between the plates and the nuts of the bolts. This, however, is discretionary and is not essential, and the same may be said of the flanges on the clamping-plates, which may be dispensed with; but it is preferred that the flange 65 g be used and provided with notches h to form seats for the wire pickets, as shown more clearly in Fig. 4. The pickets being yielding and having a spring action, the drift cannot 70 accumulate to any great extent before the force of the current will cause the pickets to bend or spring sufficient for the drift to pass over, after which the pickets will spring back to their proper place. The pickets may be 75 disposed in a perpendicular position or at an angle, as found desirable, and the base of the fence or gate, which consists of the clamping-plates, may be made in sections and bolted together, so as to adapt it to streams of dif- 80 ferent widths.

The plate A, as previously stated, is preferably made with a flange g, having notches h, in which are seated the wire pickets C, which holds the pickets in an upright position and 85 prevents lateral displacement. The notches, however, are of such size as to allow of their lateral adjustment when necessity requires to adapt the fence to any incline of the bank of the stream, and, further, to provide for this 90 adjustment the eyes f are sufficiently large to allow the necessary movement of the lower end of the picket.

In adjusting the pickets for the purpose above described the nuts upon the bolts are 95 loosened and the pickets brought from the position shown in dotted lines, Fig. 4, to an upright position shown in full lines, this adjustment of course being required on account of the angle which the clamping-plates assume 100 on the bank of the stream, as shown. After this adjustment of the pickets is made the nuts on the bolts are screwed up and the plates brought in frictional contact with the

lower portion of the pickets that are between them, which will hold them firmly in their adjusted position. The eyes in the lower ends of the pickets may be of any desirable size 5 and shape so long as the adjustment of the pickets can be made.

The coil-spring in the pickets is considered of material importance, as it will allow the pickets to act when a sufficient pressure is 10 brought against them by the drift and will quickly restore their normal or upright position when the pressure is removed.

Should a picket become broken or injured, it can be quickly removed and replaced by a 15 new one, and every provision is made for attaining the highest excellence in a flood-fence that can be readily put up in position and that will be both strong and durable, and as each picket acts independently of the other the 20 fence is more certain in its action and less liable to become inoperative.

Having now fully described our invention, what we claim as new, and desire to secure by Letters Patent, is—

25 1. In a flood-fence, the combination, with wire pickets having spring-coils, of clamping-

plates between which the pickets are held and means for anchoring said plates upon the bed of the stream, substantially as and for the purpose set forth. 30

2. In a flood-fence, the combination, with independently-adjustable pickets, of clamping-plates between which the pickets are held, one of said plates having a notched flange to form seats for the wire pickets, substantially 35 as and for the purpose specified.

3. In a flood-fence, the combination, with the pickets having coiled springs and eyes, of clamping-plates held together by suitable bolts, which pass through the plates and the 40 eyes of the pickets, one of said plates having a notched flange, substantially as and for the purpose set forth.

In testimony that we claim the above we have hereunto subscribed our names in the 45 presence of two witnesses.

HERALD CATLETT.
EDWIN ROBERTSON.
